United States Patent Office

Des. 191,424
Patented Sept. 26, 1961

191,424

REGULATOR OR SIMILAR ARTICLE

Leila Rae Davies, East Cleveland, Ohio, assignor to The Weatherhead Company, Cleveland, Ohio, a corporation of Ohio

Filed Nov. 2, 1960, Ser. No. 62,713

Term of patent 14 years

(Cl. D78—1)

Fig. 2

Fig. 1

Fig. 3

Fig. 4

Fig. 5

FIG. 1 is a side elevational view of a regulator showing my new design;

FIG. 2 is a top plan view of the regulator;

FIG. 3 is a bottom plan view of the regulator;

FIG. 4 is an elevational view taken from the left of FIG. 1; and

FIG. 5 is an elevational view taken from the right of FIG. 1.

I claim:

The ornamental design for a regulator or similar article, as shown.
